Primary Examiner — Barbara Fox

Assistant Examiner — Alexandria Dubrus

(57) **CLAIM**

The ornamental design for a saddlebag, as shown and described.

DESCRIPTION

FIG. 1 is a front-top perspective view of a saddlebag showing my new design;

FIG. 2 is a front-bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines in the drawings illustrate portions of the saddlebag which form no part of the claimed design, including lines of stitching and the zipper.

1 Claim, 8 Drawing Sheets
